UNITED STATES PATENT OFFICE.

ALBERT WORMAN, OF NEW YORK, N. Y.

AEROPLANE.

Application filed November 3, 1925. Serial No. 66,456.

The object of my invention is to simplify, cheapen and render more safe and effective both the construction and operation of aeroplanes generally, a distinctive feature being the dispensing with the use of propeller blades and the hydro-carbon motors by which they are driven, thereby eliminating noise and danger of fire and explosion,— the invention consisting substantially in the 5 substitution of vibratory wings in lieu of the usual screw blade propeller, and of electro-magnetic drive means in lieu of gas motor, all as hereinafter fully set forth and described and claimed specifically, an incidental advantage attained being the electrical control of all operations of the mechanism involved.

In the accompanying drawings I illustrate a practical embodiment of the essential features of my invention in conjunction with an aeroplane having duplex fixed planes in a manner well known in the art, although I do not wish to restrict myself to the identical form and construction of plane or operative parts shown by way of exemplification, since changes may be made in minor details, and equivalent mechanical expedients resorted to with like results, and without departing from the spirit and intent of 30 my invention in this respect.

With this understanding:—

Fig. 1, represents a side elevation of my improved aeroplane;

Fig. 2, a top view thereof;

Fig. 3, a diagrammatic view of the electro-magnetic plane wing-controlling means, with one of the said wings in side elevation;

Fig. 4 is a top view of the plane wing shown in Fig. 3;

Fig. 5 is a transverse section taken upon plane of line 5—5, Fig. 3;

Fig. 6 is a side view of the tail end propulsive wings and connections;

Fig. 7 is a transverse sectional elevation thereof taken upon plane of line 7—7, Fig. 1;

Fig. 8 is a plan of the parts shown in Fig. 6;

Fig. 9 is an elevation of the electric control means;

Fig. 10 is a transverse sectional elevation taken upon plane of line 10—10, Fig. 9;

Fig. 11 is a section taken upon plane of line 11—11, Fig. 10;

Fig. 12 is a section taken upon plane of line 12—12, Fig. 10;

Fig. 13 is a sectional detail, upon a larger scale, showing the electrical connection between control motor and cable.

The forward part of the body A, of the 60 aeroplane is provided with the usual fixed top and side planes P, P, on the rear edges of each of which are articulately mounted series of vibratory propulsive wings w, made up of like units, one of which is shown in detail in Figs. 3 and 4, each consisting of a wing blade w, attached to one end of an elastic resilient plate w', the other end of said elastic resilient plate w', being rigidly secured to the rear edge of one of the body 65 planes P, and the wing blade w, being tapered gradually in thickness to the rear end thereof.

Near its forward extremity each wing blade w, is formed with an armature a, and 70 on either side thereof are positioned electro-magnets m, m, the cores of which face the armature a, and alternately attract it as the electro-magnets m, are energized successively. The shifting of the electric current 75 from one magnet to the other is effected automatically by means of a contact piece w², on the elastic resilient wing supporting plate w', which engages alternately with the contact points m', m', connected each with the coil of one of the electro-magnets m, the 80 coils of the latter being in turn connected indirectly with a storage battery S, shown symbolically in Fig. 3, of the drawings, which figure also illustrates the co-relation 85 of the electric circuit control means C, shown upon a larger scale and in detail in Figs. 9 to 13 inclusive, of the drawings.

The tail propulsive wing blades are 90 mounted, actuated, and controlled in substantially the same way as the plane propulsive wings, except that they are pivotally supported, as at y, Fig. 6, on brackets secured to the magnets m, m.

D is the rudder actuated by well known 100 means connected therewith through the tube d, positioned centrally on the rear frame d', of the aeroplane A.

The electric circuit control means C, consists essentially of a rotor R, on the shaft r, 105 of which are rigidly mounted a plurality of commutators K', K², K³, of different diameters, and different number of peripheral contacts k', k², k³, as will be seen by reference more particularly to Figs. 9 and 10, of 110 the drawings, which illustrates the provision of three such differential time commu-

tators, although I do not restrict myself in this respect, since any plural number thereof may be used, as may be found most expedient in attaining desired variations in speed of propulsive wing action.

In the arrangement illustrated in Figs. 9 to 12, inclusive, the commutator K' , is provided with twelve peripheral contacts k' ; the commutator K^2 , with eight peripheral contacts k^2 ; and the commutator K^3 , with four peripheral contacts k^3 .

The rotor shaft r , is hollow, and the commutators K' , K^2 , K^3 , are channeled radially to accommodate the conductive wires which connect each contact plate k' , k^2 , k^3 , with an axial wire e , (see Fig. 11) which extends through the shaft r , to the left hand bearing E , and to accommodate conductive wires to an axial wire e' , (see Fig. 12) which extends through the shaft r , to the right hand bearing E' .

Hence, as the rotor R , turns its shaft r , alternately connected contact plates on each commutator K' , K^2 , K^3 , will be brought successively into engagement with the brushes B' , B^2 , B^3 , which are wire connected with the switch board B , the key lever b , of which is electrically connected with one side of the storage battery plant S , while the bearings E , E' , are in electrical connection with the other side of said storage battery plant S . As a consequence of this arrangement the electric currents transmitted to the opposed electro-magnets m , m , included in the system of wiring will be energized alternately, thereby causing them to alternately attract the armatures a , and thus vibrate the propulsive wings w , w .

The bearings E , E' , are duplicates in so

far as connection with the axial wires e , e' , are concerned, in that each of said axial wires e , e' , terminates in a disc head e^x , against which an elastic resilient contact in the preferred form of a coiled spring x , presses, said elastic resilient contact x , being in electrical connection with one or the other of the circuit wires of the system, as will be understood by reference more particularly to Fig. 13, of the drawings, which shows the right hand bearing E' , in sectional detail, it being understood as before intimated that the left hand bearing E , is of like construction and arrangement of parts, and that the disc head e^x , rotates with the rotor shaft r , whereas the elastic resilient contact x , is, relatively, stationary, maintaining electrical contact with said disc head e^x , without interfering with the rotation thereof.

It is thus obvious that by means of the key lever b , on the switch board B , the speed of vibration of the propulsive wings w , may be varied within certain prescribed limits and in accordance with requirements.

What I claim as my invention and desire to secure by Letters Patent, is:

In combination with an aeroplane of the character designated, a plurality of vibratory propulsive wings mounted on the planes thereof and a plurality of propulsive wings mounted on the rear portion thereof, electro-magnetic means for actuating said wings, and means for varying the speed of operation, consisting of a switch board, a rotor, and a plurality of commutators of different diameters interposed in the operative electric circuit, substantially in the manner and for the purpose set forth.

ALBERT WORMAN.
